UNITED STATES PATENT OFFICE.

ROBERT A. TRIBBLE, OF CEDARBLUFF, MISSISSIPPI.

VENDING APPARATUS.

1,350,088.

Specification of Letters Patent. Patented Aug. 17, 1920.

Application filed March 21, 1919, Serial No. 284,122. Renewed April 23, 1920. Serial No. 376,174.

To all whom it may concern:

Be it known that I, ROBERT A. TRIBBLE, a citizen of the United States, residing at Cedarbluff, in the county of Clay and State 5 of Mississippi, have invented certain new and useful Improvements in Vending Apparatus, of which the following is a specification.

This invention relates to a vending apparatus and more particularly to an apparatus of the self-serving variety wherein the customer is permitted to help himself from a displayed stock of goods. A structure of this general nature has been illustrated in 15 my co-pending application Serial No. 280,745 filed March 5th, 1919, and the present application has for its object to provide structures embodying all of the advantages incident to the self serving features while providing a maximum of display space.

As was set forth in the aforesaid application the self-serving store aims to display the entire stock of goods to each and every customer, to keep the crowd moving always 25 in one direction to avoid confusion and congestion, to direct all customers to a common exit and past a cashier's desk and to prevent the passage of customers from the store through any other than the last named exit. 30 At the same time it is highly desirable to so arrange the fixtures by which the foregoing results are achieved as to secure the maximum amount of wall or shelf room.

In the accompanying drawings in which 35 like reference characters designate corresponding parts:

Figure 1 is a diagrammatic plan view illustrating one form of the invention.

Fig. 2 is a like view of another form of 40 the invention.

Fig. 3 is a like view of still another form of the invention and,

Fig. 4 is a like view of a fourth form.

It will be noted that the three forms of 45 the invention illustrated in Figs. 1, 2 and 3 have a feature in common in that they each comprise an irregularly shaped central structure 5 so shaped as to provide the indented portions 6 in the sides thereof into 50 which the barriers 7; which extend obliquely from the corners of the building 8, project. The structure 5 may be a partition which extends to the ceiling but it is preferably formed by a display shelf or counter 1 which case the space 9 within the interior

thereof may be utilized for the reception of employees who wrap packages or the like.

In each of the instances mentioned an inlet turnstile 10 permits the passage of customers into the store but prevents exit 60 thiereby while an outlet turnstile 11 permits the passage of customers from the store but prevents the entry of customers at that point. Barriers 12 which extend from the structure 5 to the front of the store separate the turnstiles from each other and require persons entering the store to go entirely around the structure 5 and during their travel therearound they are caused to pass within sight of all the goods displayed 70 in the store. A cashier's cage or station 13 is arranged adjacent each of the exit turnstiles 11 at which the cost of the goods selected may be computed and the charges therefor paid.

I preferably employ a storage room 14 in conjunction with the forms described which is connected with the storeroom A by doors 15 and with the exterior of the building by doors 16. These storage rooms are intended 80 to contain supplies of goods from which the shelves and display counters within the store may be replenished from time to time. However the spaces 9 may be utilized for this purpose if desired.

While the doors 15 and 16 are normally kept closed and are used only by employees they may serve as emergency exits in case of fire. The barriers 7 may be merely fences or they may carry shelves 7' as indicated. 90 Shelves 17 extend along the several walls of the store and serve to receive goods to be sold.

In the form of the invention illustrated in Fig. 4 the entrance to the interior of the store 20 is through a turnstile 21, thence around the oval display counter 22 and through an opening 23, therein to a space 24, thence around the oval display counter 25 and through an opening 26 therein to a 95 space 27, thence around the outer side of an oval display counter 28 and through an opening 29 therein to the interior of the latter counter, thence up a flight of stairs 30 to a balcony which extends entirely around 100 the building and leads back to a flight of stairs 31 by which the customers may pass back to the main floor and out of the exit turnstile 32 after settling for the goods purchased at the cashier's desk 33. A storag 110

room 34 preferably has a shelf 35 along its front wall which conforms in the general direction of its curvature to the oval counter 22.

It is to be understood that the invention is not limited to the precise construction set forth but that it includes within its purview whatever changes fairly come within the terms or the spirit of the appended claims.

Having described my invention what I claim is:—

1. In a device of the character described the combination with a storeroom, a display structure located therein comprising a substantially continuous barrier which surrounds an interior space, said barrier being shaped to form deeply indented portions and being adapted to receive and display goods, barriers projecting into said indented portions from the walls of the storeroom, en-

trance and exit structures and means for preventing the passage of persons from the entrance to the exit structure except around the display structure.

2. In a device of the character described the combination with a storeroom, a display structure located therein comprising continuous walls which surround an interior space, said walls being of zig-zag formation to form indented portions, display shelves 30 carried by said continuous walls, non-reversible entrance and exit structures and a barrier extending from the display structure to a wall of the storeroom preventing the passage of persons from the entrance to 35 the exit structure except around the display structure.

In testimony whereof I affix my signature.

ROBERT A. TRIBBLE.
